GOVERNOR FOR INTERNAL-COMBUSTION ENGINES

Marion Mallory, Detroit, Mich.

Application October 9, 1944, Serial No. 557,831

9 Claims. (Cl. 123—103)

This invention relates to a governor for an internal combustion engine, and in particular to a governor for an internal combustion engine which is operated by a suction device connected into the intake manifold and provided with an air bleed which is controlled by a centrifugally unbalanced valve rotated in accordance with the engine speed. Such a governor is shown in my copending application Serial No. 466,961, filed November 25, 1942. In some instances, instead of air bleeding the suction device directly to atmosphere, it has been considered desirable to air bleed into the intake passageway under the air cleaner and on the atmosphere side of the governor valve to prevent dirt and dust from going into the engine. Since all air cleaners offer some restriction to the air flow into the intake passageway, a vacuum or suction is present in the intake passageway and therefore the suction device cannot be bled down to atmospheric pressure or bled down to as low pressure as is possible when the air bleed is directly to atmosphere. If the vacuum or suction in the suction device cannot be eliminated, the governor valve will not completely open.

It is the object of this invention to produce an engine governor of the above described type wherein the suction device can be air bled into the intake passageway beneath the air cleaner and which will function satisfactorily to control the speed of the engine at the desired governed speed.

Fig. 1 is a view partly in section showing my engine governor with the air bleed connected into the intake passageway beneath the air cleaner.

The parts of my governor are referenced as follows: engine intake manifold 1, intake passageway 2, air cleaner 3, governor valve 4 of the butterfly type, crank arm 5 fixed on valve shaft 6, tension spring 7 connected to crank arm 5 and tending to open valve 4, a suction actuated device comprising a housing 8 divided by flexible diaphragm 9 into chambers 10 and 11, rod 12 connecting diaphragm 9 to crank arm 5, conduit 13 connecting suction chamber 10 into the intake passageway 2 on the engine or outlet side of valve 4, conduit 14 connecting conduit 13 into the venturi 15 in intake passageway 2, conduit 16 connecting suction chamber 10 at all times with passageway 17 in the engine distributor shaft 18, centrifugal valve housing 19 which rotates with shaft 18, valve cylinder 20 communicating at all times with passageway 17, centrifugally unbalanced piston valve 21 reciprocably mounted in cylinder 20, air bleed orifice

22 controlled by centrifugally unbalanced valve 21, tension spring 23 tending to oppose closing of valve 21, passageway 24 in valve 21 permitting restricted air flow between orifice 22 when open and passageway 17, conduit 25 connecting the sealed distributor housing 26 with intake passageway 2. The inlet end 27 of conduit 25 is preferably turned upwardly directly into the air flow. Conduit 28 connects conduit 25 with chamber 11. Chamber 11 is a sealed chamber and communicates with atmosphere only through conduits 28, 25, intake passageway 2 and air cleaner 3. Manually operated throttle valve 30 which may be omitted if desired.

The operation of my device is as follows: As shown in the drawing, the engine has attained its governed speed, centrifugal valve 21 has closed or throttled air bleed orifice 22 so that the intake passageway suction on the engine side of valve 4 has drawn flexible diaphragm 9 to the right and closed governor throttle valve 4. If the load on the engine is increased, the engine speed will slow down slightly causing spring 23 to open centrifugal valve 21 thereby permitting air to flow from intake passageway 2 through conduit 25, orifice 22, passageway 17 and conduit 16 into chamber 10, thereby increasing the pressure in chamber 10 which permits spring 7 to move valve 4 toward open position. As valve 4 moves toward open position a greater charge is admitted through air cleaner 3 and through intake passageway 7. The farther that governor valve 4 is opened, the greater the charge admitted through intake passageway 2, and since air cleaner 3 will offer some restriction to air flow there will be an appreciable vacuum or suction created at orifice 27 which will prevent the vacuum in chamber 10 from being absolutely eliminated. However, since this suction or vacuum obtaining on the atmosphere side of valve 4 and also created by air flow past inlet 27 is imposed through conduits 25 and 28 upon chamber 11, this vacuum will compensate or counterbalance the inability of the centrifugally controlled air bleed 25, 21, 17 and 26 to bleed down suction chamber 10 to atmospheric pressure. In other words, this vacuum or suction imposed upon chamber 11 assists the leftward movement of diaphragm 9 and assists spring 7 to completely open governor valve 4 if load conditions call for a complete opening of the throttle governor valve. Thus, by sealing off chamber 11 and imposing the same vacuum on chamber 11 as air bleed inlet 27 acting through conduits 25, orifice 22 and conduits 17, 16 imposes upon suc-

tion chamber 10, I have completely negated the otherwise harmful effect of air bleeding suction chamber 10 into the intake passageway beneath the air cleaner rather than directly to atmosphere. It is obvious that if conduit 28 were eliminated and chamber 11 was open to atmosphere that the valve 4 would never completely open because of the inability of air bleed inlet 27 to completely eliminate the vacuum or suction in chamber 10.

I claim:

1. In an internal combustion engine having an intake passageway, a governor valve for controlling the flow of motive fluid through said passageway, fluid pressure actuated means connected to said governor valve for imparting movement to the same, a conduit connecting one side of said pressure actuated means into the intake passageway on the engine side of said governor valve, an air bleed for the same side of said pressure actuated means into the intake passageway on the atmosphere side of said governor valve, means for controlling said air bleed in accordance with engine speed and tending to close said air bleed whenever the engine attains a predetermined desired governed speed, and a conduit connecting the other side of the pressure actuated means into the intake passageway on the atmosphere side of said governor valve whereby any vacuum obtaining in the intake passageway in the vicinity of the air bleed is imposed upon both sides of said pressure actuated means and cancels itself out and the pressure actuated means can move the governor valve to wide open position whenever the speed controlled means opens said air bleed.

2. In an internal combustion engine having an intake passageway, a governor valve for controlling the flow of motive fluid through said passageway, fluid pressure actuated means connected to said governor valve for imparting movement to the same, a conduit connecting one side of said pressure actuated means into the intake passageway on the engine side of said governor valve, an air bleed for the same side of said pressure actuated means into the intake passageway on the atmosphere side of said governor valve, centrifugally controlled valve means for controlling said air bleed in accordance with engine speed and tending to close said air bleed whenever the engine attains a predetermined desired governed speed, and a conduit connecting the other side of the pressure actuated means into the intake passageway on the atmosphere side of said governor valve whereby any vacuum obtaining in the intake passageway in the vicinity of the air bleed is imposed upon both sides of said pressure actuated means and cancels itself out and the pressure actuated means can move the governor valve to wide open position whenever the speed controlled means opens said air bleed.

3. In an internal combustion engine having an intake passageway, a governor valve for controlling the flow of motive fluid through said passageway, two substantially air-tight chambers, a movable wall separating said chambers and responsive to fluid pressure differences in the said chambers, a connection between said pressure actuated wall and the governor valve for imparting movement thereto, a conduit connecting one of said chambers into the intake passageway on the engine side of said governor valve, an air bleed for said last mentioned chamber into the intake passageway on the atmosphere side of said governor valve, means for controlling said air bleed in accordance with engine speed and tending to

close said air bleed whenever the engine attains a predetermined desired governed speed, and a conduit connecting the other of said chambers into the intake passageway on the atmosphere side of said governor valve whereby any vacuum obtaining in the intake passageway in the vicinity of the air bleed is established in both chambers when the speed control means opens the air bleed and the pressure actuated wall can move the governor valve to open position.

4. In an internal combustion engine having an intake passageway, a governor valve for controlling the flow of motive fluid through said passageway, fluid pressure actuated means connected to said governor valve for imparting movement to the same, a conduit connecting one side of said pressure actuated means into the intake passageway on the engine side of said governor valve, an air bleed for the same side of said pressure actuated means into the intake passageway on the atmosphere side of said governor valve, a centrifugally unbalanced valve for controlling said air bleed in accordance with engine speed and tending to close said air bleed whenever the engine attains a predetermined desired governed speed, said centrifugal valve constituting its own centrifugal weight for unbalancing the same, and a conduit connecting the other side of the pressure actuated means into the intake passageway on the atmosphere side of said governor valve whereby any vacuum obtaining in the intake passageway in the vicinity of the air bleed is imposed upon both sides of said pressure actuated means and cancels itself out and the pressure actuated means can move the governor valve to wide open position whenever the speed controlled means opens said air bleed.

5. In an internal combustion engine having an intake passageway, a governor valve for controlling the flow of motive fluid through said passageway, fluid pressure actuated means comprising a substantially air-tight housing and a flexible diaphragm dividing said housing into two chambers, a connection between said flexible diaphragm and the governor valve for imparting movement to the governor valve, a conduit connecting one of said chambers into the intake passageway on the engine side of said governor valve whereby the suction obtaining in the intake passageway on the engine side of said governor valve is imposed on the flexible diaphragm for closing said governor valve, an air bleed for said last mentioned chamber into the intake passageway on the atmosphere side of said governor valve, means for controlling said air bleed in accordance with engine speed and tending to close said air bleed whenever the engine attains a predetermined desired governed speed whereby the intake passageway suction is established in said chamber and causes said diaphragm to move said governor valve toward closed position, and a conduit connecting the other of said chambers into the intake passageway on the atmosphere side of said governor valve whereby any vacuum obtaining in the intake passageway in the vicinity of the air bleed is established in both of said chambers when the speed controlled means opens said air bleed and the pressure actuated means can open the governor valve.

6. In an internal combustion engine having an intake passageway, a governor valve for controlling the flow of motive fluid through said passageway, fluid pressure actuated means comprising a substantially air-tight housing and a flexible diaphragm dividing said housing into two

chambers, a connection between said flexible diaphragm and the governor valve for imparting movement to the governor valve, resilient means tending to open said valve, a conduit connecting one of said chambers into the intake passageway on the engine side of said governor valve whereby the suction obtaining in the intake passageway on the engine side of said governor valve is imposed on the flexible diaphragm for closing said governor valve, an air bleed for said last mentioned chamber into the intake passageway on the atmosphere side of said governor valve, means for controlling said air bleed in accordance with engine speed and tending to close said air bleed whenever the engine attains a predetermined desired governed speed whereby the intake passageway suction is established in said chamber and causes said diaphragm to move said governor valve toward closed position, and a conduit connecting the other of said chambers into the intake passageway on the atmosphere side of said governor valve whereby any vacuum obtaining in the intake passageway in the vicinity of the air bleed is established in both of said chambers when the speed controlled means opens said air bleed and said resilient means can open the governor valve.

7. In an internal combustion engine having an intake passageway, a governor valve for controlling the flow of motive fluid through said passageway, fluid pressure actuated means connected to said governor valve for imparting movement to the same, a conduit connecting one side of said pressure actuated means into the intake passageway on the engine side of said governor valve, a rotary valve housing rotated in accordance with the engine speed, a conduit connecting said rotary housing with the last mentioned side of said pressure actuated means, a conduit connecting said housing with the intake passageway on the atmosphere side of said governor valve, a centrifugally unbalanced valve reciprocably mounted in said valve housing for controlling communication between said last two mentioned conduits and tending to close said

communication whenever the engine attains a predetermined desired governed speed, and a conduit connecting the other side of the pressure actuated means into the intake passageway on the atmosphere side of said governor valve whereby any vacuum obtaining in the intake passageway on the atmosphere side of the governor valve will be established in both sides of said pressure actuated means and cancel itself out and the pressure actuated means can move the governor valve to open position whenever the speed controlled centrifugal valve is open.

8. In an internal combustion engine having an intake passageway, a governor valve for controlling the flow of motive fluid through said passageway, an air cleaner connected to said intake passageway on the atmosphere side of said governor valve, fluid pressure actuated means connected to said governor valve for imparting movement to the same, a conduit connecting one side of said pressure actuated means into the intake passageway between the governor valve and said engine, an air bleed for the same side of said pressure actuated means into the intake passageway between said air cleaner and the said governor valve, means for controlling said air bleed in accordance with engine speed and tending to close said air bleed whenever the engine attains a predetermined desired governed speed whereby the pressure actuated means responds to move said governor valve toward closed position, and a conduit connecting the other side of the pressure actuated means into the intake passageway between the air cleaner and the governor valve whereby any vacuum obtaining in the intake passageway in the vicinity of the air bleed is imposed upon both sides of said pressure actuated means and cancels itself out and the pressure actuated means can move the governor valve to wide open position whenever the speed controlled means opens said air bleed.

9. The combination as set forth in claim 1 including a restriction to fluid flow located adjacent the inlet end of said intake passageway.

MARION MALLORY.
